UNITED STATES PATENT OFFICE.

JOSEPH BURGER, OF FAIRBURY, ILLINOIS.

IMPROVEMENT IN NOSE-JEWELS FOR SWINE.

Specification forming part of Letters Patent No. 147,368, dated February 10, 1874; application filed December 3, 1873.

To all whom it may concern:

Be it known that I, JOSEPH BURGER, of Fairbury, in the county of Livingston and in the State of Illinois, have invented an Improvement in Rings or Nose-Jewels for Swine; and do hereby declare that the following is a full, clear, and exact description thereof, reference being had to the annexed drawings making a part of this specification, in which like letters of reference refer to like parts, and in which—

Figure 1 represents a perspective view of forked ring or nose-jewel before insertion; Fig. 2, front elevation after insertion; Fig. 3, side elevation.

The object of this invention is to prevent hogs from rooting; and it consists of an oblong plate having two parallel prongs or forks branching off at right angles thereto, and tapering each to a point, which are inserted in the hog's nose by a pair of pinchers or pliers suitably constructed for the purpose, as will be hereinafter more fully explained, and pointed out in the claim.

In the drawings, A represents a jewel for swine having two parallel prongs or forks, b, long enough to pass through the gristle of the snout, and which branch at a right angle from

a small oblong plate, a, about one-half or one-third of an inch in diameter. These each taper to a point, c, the more readily to bend up when inserted, or during insertion, so as to prevent their return through the puncture, being inserted by first placing the plate a within a slot in the upper jaw of the pliers C, with the prongs b at a right angle therewith, in the best position for passing them through the snout, which is done by closing the pliers. The lower jaw of the latter, meeting the points c c after their passage through the snout of the hog, bends them upward or sidewise, and prevents the jewel from coming out.

What I claim as my invention is—

The snout-jewel for swine, A, consisting of plate a, having double prongs or forks b b, tapered each to a point, and bent during insertion to retain the jewel, substantially as and for the purposes set forth.

In testimony that I claim the foregoing improvement in swine-jewels I have hereunto set my hand this 25th day of November, 1873.

JOSEPH BURGER.
